UNITED STATES PATENT OFFICE.

FRANK GUSTAVESON, OF WABASHA, MINNESOTA.

HEAT-RETAINING MEANS FOR WAXED-THREAD SEWING-MACHINES.

1,070,338.

Specification of Letters Patent. Patented Aug. 12, 1913.

Application filed July 2, 1912. Serial No. 707,294.

To all whom it may concern:

Be it known that I, FRANK GUSTAVESON, a citizen of the United States, residing at Wabasha, in the county of Wabasha and 5 State of Minnesota, have invented new and useful Improvements in Heat-Retaining Means for Waxed-Thread Sewing-Machines, of which the following is a specification.

10 The invention relates to sewing machines utilizing a waxed thread and has for its object to maintain the waxed thread at such a temperature as to prevent its breaking when forming the stitch as frequently happens when the thread becomes cooled to such 15 extent as to prevent its free passage through the eye of the needle and the shuttle.

The invention contemplates a housing for 20 inclosing the working parts of the sewing machine and for directing the heat upon the thread in such a manner as to keep the wax soft during the sewing operation, thereby preventing snapping or breaking of the 25 thread.

A further purpose of the invention is the provision of a housing which may be separate from and applied to the machine or which may form a part thereof, said housing 30 being of such construction as to admit of access being readily had to the working parts of the machine for adjustment, oiling 35 cleaning or other purpose.

The invention consists of the novel features, details of construction and combination of parts, which hereinafter will be more particularly set forth, illustrated in the accompanying drawings, and pointed out in the appended claims.

40 Referring to the drawings, forming a part of the specification, Figure 1 is a perspective view of a sewing machine using a waxed thread provided with heat retaining means embodying the invention, the parts being 45 shown in closed position. Fig. 2 is a view similar to Fig. 1, the parts of the housing being open to expose the working parts of the sewing machine so that access may be readily had thereto.

50 Corresponding and like parts are referred to in the following description, and indicated in all the views of the drawings, by the same reference characters.

The sewing machine illustrated is of the 55 type designed chiefly for sewing leather or other goods requiring a waxed thread and

which embodies a wax pot or other receptacle maintained at a proper temperature to keep the wax in a soft condition so as to be readily taken up by the thread which is caused to pass therethrough. 60

The present invention relates to the means for confining the heat and directing the same upon the thread to prevent its breaking during the stitching operation, said means being in the nature of a housing inclosing the working parts with the exception of a space for the introduction and manipulation of the work during the operation of the machine in stitching. 65

The invention contemplates a housing which varies according to the style or make of machine to which the invention is adapted, said housing forming a part of such machine or being separate therefrom 70 and secured thereto in any practical way. 75

The housing comprises essentially two parts which are applied to respectively the upper and the lower portions of the sewing machine. The upper part of the housing is 80 in the nature of a hood 1 which has an opening in its top adapted to be closed by means of a door 2 which is preferably hinged at its inner or rear edge to the housing so that its front portion may be thrown upwardly and 85 rearwardly so as to be out of the way when access is required to be had to the upper part of the sewing machine mechanism. The front portion of the hood 1 is contracted and slopes upwardly at its outer end, thereby 90 providing ample space for the introduction and manipulation of the work.

The lower part of the housing is closed at its front by means of (a middle and side swinging doors,) the middle door opening 95 downwardly and the side doors opening outwardly. When the three doors are closed the lower portion of the sewing machine mechanism is completely inclosed, thereby confining the heat from the burner or other type of 100 heater employed for keeping the wax soft in the wax pot or receptacle. The middle door 3 has side flanges 4 which extend along the sides of the projecting mechanism of the machine so as to inclose the same. The side 105 doors 5 have bottom flanges 8 and vertical flanges 7, the latter fitting close against the side flanges 4 of the middle door so as to confine the heat. Either one of the doors may open independently without disturbing the 110 others so that access may be had to a particular part of the sewing machine for any pur-

pose that may be required. When the several doors are closed the mechanism of the sewing machine is housed with the exception of that directly opposite the stitching mechanism and designed to receive the work, hence the heat from the burners is confined and when escaping finds an outlet through the space intended to receive the work, thereby keeping the wax upon the thread sufficiently soft during the stitching operation to prevent snapping or breaking.

From the foregoing description, taken in connection with the accompanying drawings, the advantages of the construction and 15 of the method of operation will be readily apparent to those skilled in the art to which the invention appertains, and while I have described the principle of operation of the invention, together with the device which I 20 now consider to be the best embodiment thereof, I desire to have it understood that the device shown is merely illustrative, and that such changes may be made when desired as are within the scope of the claims 25 appended hereto.

Having thus described the invention what is claimed as new, is:—

1. In a sewing machine of the type utilizing a waxed thread, a housing for confining 30 the heat and directing the same upon the thread, said housing embodying upper and lower portions, the upper portion consisting of a hood and the lower portion (being closed by three front doors, the middle door 35 being hinged to swing downwardly and the side doors to swing outwardly, the several doors fitting closely at their meeting edges and each adapted to open independently of the other.

40 2. In a sewing machine of the variety em-

ploying a waxed thread, a housing for confining the heat and directing the same upon the thread, said housing being closed by three front doors, the middle door being hinged to swing downwardly and having 45 flanges at its vertical edges and the side doors being hinged to swing outwardly and having flanges at their lower and vertical edges, the flanges at the vertical edges of the side doors closing against the flanges at 50 the edges of the middle door, the parts being arranged to admit of any one of the doors being opened independently of the others.

3. A housing for sewing machines of the nature utilizing a waxed thread, said housing consisting of an upper hood having its outer portion contracted and its lower portion sloping upwardly, said hood having an opening in its top which is adapted to be closed by an upwardly swinging door, said housing further embodying a lower portion (which is spaced at its front) from the hood to admit of access being readily had to the stitching mechanism, (and which is closed by three doors, the middle door being hinged 60 to swing downwardly and having flanges at its vertical edges and the side doors being mounted to swing outwardly and having flanges at their lower and vertical edges, the vertical flanges of the side doors closing 65 against the flanges of the middle door, the parts being arranged to admit of any one of the doors being opened independently of the others.

In testimony whereof I affix my signature in presence of two witnesses.

FRANK GUSTAVESON.
